DESIGN FOR A MAN'S SLEEPING ROBE

Arthur Berger, New York, N. Y.

Application September 22, 1941, Serial No. 103,450

Term of patent 3½ years

To all whom it may concern:

Be it known that I, Arthur Berger, a citizen of the United States of America, residing in New York city, county of New York, and State of New York, have invented a new, original, and ornamental Design for a Man's Sleeping Robe, of which the following is a specification, reference being had to the accompanying drawing, forming part thereof.

Fig. 1 is a front view of a man's sleeping robe showing my new design.

Fig. 2 is a rear view thereof.

Fig. 3 is a fragmentary view of the upper portion of the man's sleeping robe showing the collar in closed position.

I claim:

The ornamental design for a man's sleeping robe, substantially as shown.

ARTHUR BERGER.
